UNITED STATES PATENT OFFICE.

GEORGE W. BAYLEY, OF NEW YORK, N. Y., ASSIGNOR TO BAYLEY & SONS, INC., OF BROOKLYN, NEW YORK, A CORPORATION OF NEW YORK.

DESIGN FOR AN ELECTRIC-LIGHTING FIXTURE.

49,593.

Specification for Design.

Patented Sept. 5, 1916.

Application filed March 25, 1916. Serial No. 86,819. Term of patent 7 years.

To all whom it may concern:

Be it known that I, GEORGE W. BAYLEY, a citizen of the United States, resident of the borough of Brooklyn, county of Kings, city and State of New York, have invented a new, original, and ornamental Design for an Electric-Lighting Fixture, of which the following is a specification, reference being had to the accompanying drawings, forming a part thereof.

In the drawings, Figure 1 is a top view; and Fig. 2 is a side view.

The design comprises a bell-shaped canopy having a straight lower edge. Below the

canopy is suspended a hemispherical bowl having a straight upper edge in close proximity to the straight lower edge of the canopy. The bowl is severely plain in outline.

I claim:

The ornamental design for an electric lighting fixture, substantially as shown and described.

Dated, March 21st, 1916.

GEORGE W. BAYLEY.
